DOOR LOCKS OR LATCHES

Harold Thorne, 12 Cadogan Garden, London, England

Filed Oct. 26, 1956, Ser. No. 618,610

Claims priority, application Great Britain Nov. 23, 1955

8 Claims. (Cl. 292—1)

This invention relates to door locks or latches adapted for operation by handles on both sides of the door and particularly those used in the doors of motor road vehicles, and the invention will be described hereinafter in connection with such latches.

It is usual to provide some means for deadlocking the latch from the interior of a car so that operation by the exterior handle is prevented.

The invention is particularly concerned with child safety means which are brought into operation during the running of the car and which prevent actuation of a latch from the interior of the car so that the driver's attention is not distracted from his control of the car. To this end, the deadlocking of a latch for child safety is only releasable by actuation of the exterior handle. Such an arrangement is described in the specification of my prior application No. 547,620, now Patent Number 2,877,044, issued March 10, 1959, in connection with latches in which the outer handle incorporates a press button means.

The object of the present invention is to provide improved child safety means applicable to latches operated by other than press button means.

A further object is to provide emergency means adapted automatically to release the child safety deadlocking means on impact occurring in either direction.

The invention consists in a car lock or latch adapted to be operated by an inner handle and an outer handle, wherein child safety means are provided for deadlocking the inner handle and which are brought into operation by a movement of the inner handle in a reverse direction to normal, release of the deadlocking means to be effected by the normal operation of the outer handle. The release of the child safety means may be also effected automatically by means brought into operation by impact of the car in either direction.

The child safety means may comprise an element pivotally mounted on a horizontal or other suitable axis.

The child safety means may comprise a pivotally mounted weighted latch element. Alternatively, an independent pivotally mounted weighted release member may be provided.

In the accompanying drawings:

Figure 1 is an elevation of a lock having the invention applied thereto;

Figure 2 is a sectional elevation on the line 2—2 of Figure 1;

Figure 3 is a plan;

Figure 4 is a view of a detail of the child safety device;

Figure 5 is an elevation of a modified form of child safety device;

Figure 6 is a diagrammatic view of an inner handle construction;

Figure 7 is an elevation of another form of lock having a child safety means applied thereto;

Figure 8 is an elevation at right angles to Figure 7;

Figure 9 is a plan of Figure 7;

2

Figure 10 is an elevation of a modification showing a child safety device pivoting on a vertical axis;

Figure 11 is a plan;

Figure 12 is a plan of the child safety means of Figure 10.

In carrying the invention into effect according to one convenient mode by way of example as applied to a car lock having an outer fixed handle with a press button, an inner lever handle and a sill-button anti-theft lock, see Figures 1—4, a pivotally mounted bell crank pawl lever is provided with an upwardly extending pawl arm 1 adapted for engagement with the teeth of a star wheel 2 integral or fixed to a rotary bolt. This pawl arm 1 carries a stud or projection 3. The other arm 4 of the bell crank extends horizontally and co-operates with a stop 4a. The bell crank lever 1, 4 is pivoted on a pin 5. A push button lever is pivoted on the same pin 5 as the bell crank 1, 4 and has a downwardly extending arm 6 for engagement by the push button 6a. The push button lever also has an upwardly extending arm 7 which has a horizontal slot 8 into which the stud 3 extends to provide a lost motion connection between the push button lever 6, 7 and the bell crank 1, 4. Located above these levers 6, 7 and 1, 4 is a locking lever pivoted on the pin 9 and lying more or less horizontally. This locking lever, having arms 10 and 11, is operable from the interior of the car by a sill button, the stem 12 of which engages the hole 12a in the arm 11 and is adapted upon anti-clockwise rotation to engage by a flange 13 on the arm 10 or lie in the path of the upper end 14 of the arm of the push button lever 6, 7 whereby the latter is locked against operation by the push button.

The above levers: 1, 4; 6, 7 and 10, 11 lie in planes transverse of the plane of the car door, and in the plane of the door, a lock release bell crank lever is pivotally mounted on pin 15. This lock release bell crank lever has an arm 16 the end of which is recessed and in co-operative engagement with the arm 11 of the locking lever 10, 11. A second arm 17 of this lock release bell crank extends downwardly and the end 18 thereof is adapted to be engaged by a projection 19 on the arm 20 of an inner lever handle bell crank lever pivoted on pin 21, whereby on operating the inner handle for normal operation the locking lever 10, 11 will be moved to its release position.

The inner handle bell crank has a horizontally extending arm 22 which underlies the horizontal arm 4 of the pawl bell crank lever 1, 4 whereby on actuation of the inner handle the pawl arm 1 will be moved to the release position which will occur without movement of the press button lever 6, 7 owing to the lost motion connection 3, 8 hereinbefore referred to.

Associated with the horizontal arm 22 of the inner handle bell crank 20, 22 is a "child safety" arm 23 which is pivotally mounted upon a horizontal axis. The arm 23 is provided with a weight 23a. The pivot is formed by a screw 24 (see Figure 4) located in a hole in the lock casing 25 and threaded through a sleeve 26.

The arm 23 is provided with an aperture 23b of larger diameter than the outer diameter of the sleeve 26 so that the arm is freely mounted on the sleeve and a light coiled spring 27 surrounds the sleeve and is located between the arm and the casing. A washer 28 and nut 29 holds the parts in position.

65 The arm 23 is slotted at 30 to provide a shoulder 31 with which a pin 32 on the arm 22 is adapted to co-operate.

The arm 23 is provided with a spur 33 which lies over offset portion 4' of the arm 4 of bell crank 1, 4 and a second spur 34 adapted for engagement by the projection 19 on the arm 20 of the inner handle bell crank lever.

Under normal operation of the inner handle which turns the lever 20, 22 clockwise the pin or projection 32 moves upwardly, but when the inner handle is moved from its normal position in a reverse direction turning the lever 20, 22 anticlockwise, the pin 32 is moved downwardly to engage beneath the shoulder 31 on the "child safety" arm 23 when the latter is pivoted by engagement of projection 19 with the spur 34.

Manual release of the "child safety" arm 23 is effected by the operation of the outer push button 6 which causes the horizontal arm 4 of the pawl bell crank to rise (through the engagement of the pin 3 with the end of the slot 8) and engage the spur 33 on the "child safety" arm and pivot said arm. This action moves the shoulder 31 sideways and allows the arm 22 to rise and the inner handle to return to normal.

The "child safety" arm 23 when in its operative position is also adapted for automatic release should impact occur in either direction in a direction at right angles to its pivot by utilising the inertia effect of the arm 23 operating as a pendulum. This automatic release is effected by a swing of the arm 23 on its horizontal pivot causing disengagement of the pin 32 and shoulder 31 which permits a movement of the bell crank lever 20, 22 under the action of the usual spring 42b (Fig. 6) on the inner handle 41, such movement bringing the bell crank lever 20, 22 and inner handle 41 to the "thief proof" locked position, from which the inner handle may now be moved manually to the "open position."

At the same time the mounting of the "child safety" arm permits an automatic side-wise movement (by the spring mounting 26, 27) should impact occur in this direction, such movement resulting in disengagement of the pin and shoulder 32, 31 and release of the inner handle bell crank 20, 22.

According to a modified form of "child safety" device, see Figure 5, an arm 35 is pivotally mounted at 36. The arm has a triangular projection 37 adapted for engagement with the projection 32 of arm 22. The arm 35 also has a release spur 38 for engagement by the arm 4 of bell crank 1, 4.

The arm 35 is maintained in a central position by a light leaf spring 39 one end of which is secured to the arm, the other end being anchored to a stud 40.

It will be noted that projections 32a and 37 are of triangular shape and in the unlocked position their apices are opposed to one another. When the inner handle is moved to the "child safety" position the arm 22a moves anticlockwise and the projection 32a will move down one of the slant sides of the triangular projection 37 pivoting 35 against the action of the spring 39 until 37 will snap into the position shown in Fig. 5 and lock the bell crank 22a.

In the normal operation the projection 32 lies above the triangular projection 37 but when the inner handle is moved in a reverse to normal direction, the arm 22 is lowered so that the projection 32 passes beneath the projection 37 and the "child safety" arm is set. From this position the arm may be released by operation of the outer handle, or automatically by impact in either direction which moves the projection 37 sidewise permitting the bell crank 22 to pivot and projection 32 to rise above the projection 37.

The inner handle 41 may be connected for remote control by link 42 (Figure 6) and having known setting means comprising a recessed cam plate 42a for holding it in the closed and locked positions 43 and 44, movement to the open and "child safety" positions 45 and 46 being spring returned by spring 42b to the closed and locked positions respectively.

Under normal operation of the inner handle 41, it is moved manually from the closed position to either the open position or the locked or thief-proof position, and during such movements the pin 42c will be pressed out

of the center recess against the action of the spring 42b, and into the recess 42e corresponding to the locked position or the recess 42f corresponding to the open position. To return the handle to the closed position, it must be operated manually, and this may be regarded as normal operation of the handle.

When the inner handle 41 is moved beyond the locked position to the "child safety" position, the part 42d will be brought into engagement with the spring pressed pin 42c, and in such position the inner handle 41 will be locked against return movement by the "child safety" member 23 (Fig. 2), and thus cannot be moved manually to unlock the door from inside the vehicle. Upon release of the member 23 by impact occurring or actuation 10 of the outer handle, the inner handle will be free to return and such return will be effected by the spring 42b moving the pin 42c along the part 42d, and pivoting 15 the handle 41 until the handle reaches the locked position, whereupon the pin will enter the recess 42e and 20 retain the handle in such position from which it may now be moved manually to the open position.

According to a modified form of lock or latch see Figures 7-9, in which the outer handle is of the pivoted lever type, such handle operates to actuate a pin 50 which engages in a slot 51 in a rectilinearly movable plate 52 which has a projection 53 adapted to engage a downwardly projecting arm 54 of a spring biased pawl plate 55 pivoted at 56. This plate has an upwardly projecting pawl 57 for actuating a star wheel 58 which is 25 operatively engaged with the locking pinion. The pawl plate 55 also has an arm 59 located at about 260° from the pawl arm 57.

The inner handle is connected for remote control by a link 60 to a bell crank release lever 61 pivoted at 35 62 and having a horizontal arm 63 which underlies the arm 59 of the pawl plate 55. The release arm 61 also carries a pin 64 hereinafter referred to.

Located beneath the release bell crank 61 is a deadlocking plate 65 pivoted at 65a and operable to a deadlocking position by a sill button similar to the sill button 40 12 shown in Figure 1.

This deadlocking plate 65 is provided with oppositely disposed arms 66 and 67 having flanges 68, 69 respectively. When moved to the deadlocking position by operating 45 the sill button the plate is turned clockwise so that the flanges 68 lies in the path of movement of a spur 70 of the bell crank release lever 61 thus deadlocking the inner handle. By the same movement the flange 69 is moved into the path of a projection 71 on the plate 52 thus deadlocking the outer push button. The inner and outer handles are thus deadlocked until released by movement of the plate 65 in anti-clockwise direction by the sill button.

Mounted on the same pivotal axis 65a as the deadlocking plate 65 is a "child safety" lever 72 having a weight 72a. The lever 72 has a notch 73 adapted to engage the pin 64 on the arm 63 of the release bell crank 61 when the latter is moved to the "child safety" position by the inner handle, i.e. by a movement of the 55 handle in a reverse direction to normal which causes the release bell crank 61 to move in a clockwise direction moving the pin 64 downwardly into the notch.

Under normal conditions the pin 64 rides up a surface 74 on the "child safety" lever 72 which latter is 60 spring biased towards the pin.

When the "child safety" lever 72 is in operation the inner handle is deadlocked and is releasable only by the operation of the outer handle (press button) which 65 causes the arm 59 of the pawl plate 55 to engage a cam surface 75 on the "child safety" lever to move it counter-clockwise. This movement of the plate 72 releases the bell crank release 61 and permits the inner handle to move under actuation of spring 42b (Fig. 6) and thus move the handle to the locked or thief-proof position from 70 75 which it may be moved manually to the "open" position.

In the above forms of the invention, the "child safety" impact release means pivots on a horizontal axis. This however, is not essential and any other suitable angle, such as vertical, may be adopted.

Thus, according to a modified form of the previous modification see Figures 10-12, a sliding latch bolt 95 is operable by inner and outer lever handles through a link 96 and bell crank lever 97 respectively.

Operation of the outer handle turns the bell crank lever 97 causing one arm 98 to engage a stud 99 on the latch bolt 95 to withdraw the latter. The second arm 100 of the bell crank lever 97 has a groove 101 into which, when the bell crank is in its normal position as shown in Fig. 12 a pin 102 on a slider 103 is adapted to engage when the slider is moved to a locking position by the inner handle to lock the outer handle. Release of the outer handle is effected by returning the inner handle to normal position thus withdrawing the pin from the groove. The inner handle is connected by the link 96 to a rod 104 which carries a lateral projection 105 located in a slot 95a in the bolt for withdrawing the bolt. The slider 103 is mounted upon the rod 104 and moves therewith.

A spring biased "child safety" catch 106 is pivotally mounted on a vertical axis 107 in a bracket 107a secured to the casing 115 and is provided with a detent 108 which is adapted to engage a part of the slider 103 when the inner handle is moved reversely to a position beyond that for normal locking. The catch 106 is spring biased towards the casing by spring 106a.

Release of the catch 106 is effected by operation of the outer handle which causes the arm 100 of the bell crank lever to engage a camming surface 109 on the "child safety" catch to pivot it about the vertical axis and release the slider 103 and inner handle. When the slider 103 is moved to the child safety position to engage detent 108, the pin 102 is moved beyond the groove 101 in the arm 100 of the outer handle bell crank lever 97 whereby the outer handle may be actuated for releasing the catch 106.

An automatic release member 110 is pivotally mounted on a vertical axis 111 on the "child safety" catch 106 and is provided with a pair of oppositely disposed arms 112, 113. A third arm is provided with a suitable weight 114.

On impact in one direction the release member 110 pivots about 111 causing the arm 113 to engage the slider thereby pivoting catch 106 about pivot 107 and thus move the catch detent 108 to release the slider, whereupon the slider will move under the action of the spring means associated with the inner handle to return the handle to the "thief proof" position from which it may be moved manually.

Impact in the other direction causes the arm 112 to engage a wall 115 of the lock mounting thus again pivoting the catch 110 and releasing the slider and inner handle.

I claim:

1. In a latch structure for a vehicle door and which latch structure is of the type that is actuated by an inner handle and an outer handle, the combination including a mounting means, a movable member carried by the mounting means and operable in one position to permit opening of such a door and in another position to prevent opening of such door, a first movable means carried by the mounting means for coupling with the outer handle, said first movable means being operably coupled with the movable member to control the positions thereof to permit opening of the door by such outer handle, a second movable means carried by the mounting means for coupling with the inner handle, said second movable means being also operably coupled with the movable member so that in response to movement of the second movable means in one direction, by actuation of such inner handle in one direction, the door can be opened by

the inner handle, child safety deadlocking means carried by the mounting means for cooperation with the second movable means in response to movement of the second movable means in the opposite direction occasioned by opposite movement of the inner handle to lock said second movable means and thereby said inner handle against subsequent movement in said one direction, and means for releasing the deadlocking means from said second movable means in response to actuation of such outer handle to open the door.

5 2. In a latch as claimed in claim 1 and said child safety deadlocking means comprising an arm, means loosely pivotally supporting said arm on the mounting means, interengaging locking components carried by said arm and said second movable means for coupling said second movable means to said arm in response to movement of the second movable means in said opposite direction, said second movable means including a component for engaging said arm to effect movement thereof to couple said interengaging locking components together, and the loose pivotal connection of the arm to the mounting means permitting uncoupling of said locking components in response to impact.

10 3. In a latch as claimed in claim 1 and said child safety deadlocking means comprising an arm, means pivotally supporting said arm on the mounting means, inter-engaging locking components carried by said arm and said second movable means for coupling said second movable means to said arm in response to movement of the second movable means in said opposite direction, and said second movable means including a component for engaging said arm to effect movement thereof to couple said inter-engaging locking components together.

15 4. In a latch structure for a vehicle door and which latch structure is of the type that is actuated by an inner handle and an outer handle, the combination including a mounting means, a bolt means movably carried by said mounting means, means for operably coupling the bolt means with the inner handle whereby the bolt means may be released by actuation of said inner handle, means for operably coupling the bolt means with the outer handle whereby the bolt means may be released by actuation of the outer handle, child safety deadlocking means carried by the mounting means, means for operably coupling

20 45 said deadlocking means with the means operably coupling the bolt means to the inner handle, including components for setting the deadlocking means by actuation of the inner handle in a direction opposite to that necessary to open the door, and means for releasing said deadlocking means in response to actuation of the outer handle.

25 5. In a latch as claimed in claim 4 and said bolt means being a rotary bolt, the means operably coupling the bolt means with the inner handle including a bell crank lever pivotally connected to the mounting means, said deadlocking means comprising an arm also pivotally connected to the mounting means, inter-engaging locking means on said bell crank lever and said arm respectively, one arm of said bell crank lever having a projection thereon, said pivotally mounted arm having a surface thereon adapted to be engaged by said projection upon movement of said one arm of the bell crank lever towards said surface, so as to move said first-mentioned arm to inter-engage said locking means when the inner handle is moved in said opposite direction, and the means operably coupling the bolt means with the outer handle including a surface engageable with said first-mentioned arm to move the same to a position to disengage said locking means.

30 6. In a latch as claimed in claim 5 and the means operably coupling the bolt means with the outer handle including a second bell crank lever, means pivotally connecting said second bell crank lever to said mounting means, said first mentioned arm having a spur thereon crossing the path of movement of said second bell crank

7 lever, and one arm of said second bell crank lever having said surface thereon that is engageable with said spur in response to actuation of the outer handle to release said inter-engaging locking means.

7. In a latch means as claimed in claim 4 and said bolt means comprising a rotary bolt, a star-wheel secured to said rotary bolt, a first bell crank lever pivotally connected to the mounting means and including a pawl arm for cooperation with the star-wheel to lock said rotary bolt against retrograde movement, the means operably coupling the bolt with the outer handle including said bell crank lever and a second pivotally mounted lever, a pin and slot lost motion connection between said bell crank lever and said second lever permitting movement of the bell crank lever independent of the movement of the second lever, the means for coupling the bolt with the inner handle including a second bell crank lever pivotally connected to said mounting means, a pivotally mounted child safety arm carried by the mounting means, said second bell crank lever having a pivot surface engageable with the child safety arm to pivot said arm in one direction, means defining a shoulder on said child safety arm, one arm of said second bell crank lever having a pin projecting therefrom, said pin and shoulder being engageable to couple the child safety arm with the second bell crank lever to prevent reverse

5 movement of the second bell crank lever, said child safety arm also having a spur thereon, the other arm of said first-mentioned bell-crank lever being engageable with said spur to release the child safety arm in response to movement of said first bell crank lever by the outer handle and said child safety arm having a weight thereon to impart disengaging movement between said shoulder and pin in response to impact.

10 8. In a latch structure as claimed in claim 7 and including a sleeve projecting from said mounting means, said child safety arm being loosely pivoted on said sleeve, light spring means biased between said arm and mounting means to permit lateral movement of the arm sufficient to release the engagement between said shoulder and pin in response to impact occurring in the direction laterally of the arm.
